HOISTING MECHANISM

1,335,782.

Specification of Letters Patent

Patented Apr. 6, 1920.

Application filed November 11, 1918. Serial No. 261,968.

To all whom it may concern:

Be it known that I, JOHN DOLAN, a citizen of the United States, residing at Dayton, in the county of Montgomery and State of Ohio, have invented certain new and useful Improvements in Hoisting Mechanism, of which the following is a specification, reference being had therein to the accompanying drawing.

10 This invention relates to hoisting mechanism.

The object of the invention is to provide a hoisting mechanism which, when in its normal or collapsed position, will be very short, but which may be extended to a relatively great length; which can be quickly and easily operated to extend or retract the same; and which will be of a very strong, durable construction and very simple in its 20 operation.

To this end it is also an object of the invention to provide a mechanism of this kind in which the several lifting elements will be normally locked against movement and will 25 be automatically and successively released, and, further, in which the several lifting elements will be locked in their extended positions and automatically released as the structure is retracted.

30 It is also an object of the invention to provide a mechanism of this kind with interchangeable operating mechanisms, either of which can be manipulated without displacing the other.

35 It is also an object of the invention to pivotally mount such a mechanism upon a portable platform and provide means for raising and lowering the same into and out of an operative position.

40 Other objects of the invention will appear as the mechanism is described in detail.

In the accompanying drawings Figure 1 is a side elevation, partly broken away, of 45 a lifting jack embodying my invention; Fig. 2 is a front elevation, partly in section, of such a lifting jack; Fig. 3 is a sectional view of the upper and lower portions of the lifting jack shown in Figs. 1 and 2; Fig. 50 4 is a side elevation of the worm gear with the pawl actuating plate removed; Fig. 5 is a sectional view, taken on the line 5—5

of Fig. 4; Fig. 6 is a side elevation of the worm gear with the pawl actuating plate in place; Fig. 7 is a side elevation, partly 55 broken away, of a portable hoisting mechanism embodying my invention; Fig. 8 is a front elevation, partly broken away, of said hoisting mechanism; Fig. 9 is a plan view of the turntable; Fig. 10 is a transverse sectional view of the turntable; Fig. 11 is a transverse sectional view of the supporting structure and lifting elements of Figs. 7 and 8; Fig. 12 is a sectional view 60 of the controlling drums of Figs. 7 and 8; 65 and Fig. 13 is a plan view of the nozzle supporting and actuating device.

In these drawings I have illustrated two embodiments of the invention, which are the same in their essential characteristics 70 but show the mechanism as adapted for different purposes. It will be understood, however, that while I have shown embodiments of the invention for two purposes that it is not limited to the particular purposes here illustrated, but that the invention can be embodied in mechanisms of various forms and for various purposes. In the two embodiments of the invention here illustrated, that shown in Figs. 1 and 2, is 75 a lifting jack such as is commonly used for automobile or street car purposes, while the embodiment shown in Figs. 3 and 4 is a hoisting mechanism for miscellaneous purposes. It may be used as a lift for elevating a load; it may be used as a hose tower, as shown in the drawings; it may be used as a support or brace for forms or other elevated structures; or it may be used for 80 any one of numerous other purposes. 90

The mechanism will, of course, take different forms, according to the different purposes for which it is to be used. The lifting jack illustrated in Figs. 1 and 2 consists of a supporting standard or base 1 provided 95 at its lower end with flanges 2 to support the same in a vertical position. This standard or base is hollow and has mounted therein a plurality of overlapping extensible lifting elements. These lifting elements may 100 take various forms, but I prefer that they should be of a telescoping construction and should be provided on their faces with teeth or racks to coöperate with the operating

mechanism. In the present construction the jack is provided with two lifting elements, the outermost of which, 3, is slidably mounted within the hollow base or standard 1 and 5 is substantially U-shaped in cross section, the forward or free edges thereof being provided with teeth as shown at 4. Mounted within the outer or U-shaped rack is a second lifting element in the form of a straight 10 bar 5, provided along its forward edge with teeth 6. The teeth of the two racks are arranged in alinement so that they may be engaged by the same actuating device. This actuating device may be of any suitable 15 character, either pawl and ratchet mechanism or rack and pinion mechanism being well adapted for the purpose. In the present instance I have employed the rack and pinion lift and, as here shown, a pinion 20 7 is journaled in the side walls of the standard 1 and extends for substantially the full width of the two lifting elements. Preferably, the pinion is carried by a shaft 8 mounted in the side walls of the standard 1 and having its ends projecting beyond the 25 respective walls. Rigidly secured to the projecting end of the shaft is a ratchet wheel 9 which is acted upon by a pawl 10 carried by a lever 11, which is bifurcated 30 and is mounted on the shaft 8 on opposite sides of the ratchet wheel. A dog 12 operates with the ratchet wheel to hold the pinion 7 against reverse movement and thus retain the lifting element or elements in 35 their elevated positions during the return movement of the lever. It will be noted that the teeth of the two racks of the outer lifting element 3 are cut away adjacent to the pinion 7 so that this outer element will 40 not be affected by the operation of the pinion until the inner rack or lifting element has been fully extended. When the inner element has been fully extended it automatically picks up the outer element and 45 carries the same upward with it until the teeth of the racks of the outer element are brought into mesh with the pinion 7, after which continued movement is imparted to the outer element by the pinion. Any suitable 50 connection may be established between the inner and outer lifting elements to cause the former to lift the latter but, preferably, the inner element has near its lower end outwardly extending lugs 13 arranged to engage inwardly extending lugs 14 carried by the outer lifting element near the upper end thereof and arranged in the paths of the respective lugs 13 on the inner element. The upper ends of the lugs 13 of the inner lifting 55 element are spaced some distance from the lower end of that element to enable the inner lifting element to be moved, by the pinion 7 after the lugs or shoulders 13 have engaged the coöperating lugs or shoulders 60 14, and thus cause the outer lifting element 65 to be elevated by the inner lifting element far enough to bring its teeth into mesh with the pinion 7. This arrangement of the lugs also causes the two lifting elements to overlap sufficiently to give rigidity to the ex- 70 tended structure.

Suitable retaining means are provided for holding the inner lifting element or rack 5 in its extended position relative to the outer lifting element during the movement of the latter. This retaining means may be of any suitable character but, in the present construction, I have provided the outer lifting element at its upper end with a collar 15 in which is journaled a pinion 16 meshing with the rack of the inner lifting element and having rigidly secured thereto, in the collar 15, a ratchet wheel 17. Coöperating with this ratchet wheel is a dog 18 which is acted upon by a spring 19 to cause 80 it to engage the ratchet wheel when the outer lifting element has been moved from its normal position, and to thus hold the pinion 16 and, consequently, the inner lifting element against downward movement. 85 This dog acts upon the ratchet wheel to retain the inner lifting element in its extended position only so long as the outer lifting element is out of its normal position and, as soon as the outer element is returned to 90 its normal position the dog is again moved into inoperative position and the inner rack released to allow the same to move downward. To accomplish this I have provided the dog 18 with a depending finger 20 arranged to engage a part of the standard 1, such as the upper end thereof, when the outer lifting element is in its normal or lowermost position, and thus retain the dog 95 in its inoperative position. The first upward movement of the outer lifting element, which is imparted thereto by the inner lifting element, carries the finger out of engagement with the standard and permits the dog to operatively engage its ratchet 100 wheel and thus lock the inner lifting element against downward movement relatively to the outer lifting element. Just as the outer lifting element completes its downward movement the finger 20 will again engage the standard and move the dog out of engagement with the ratchet wheel, thus 105 automatically releasing the inner element and permitting the downward movement of the load to continue uninterrupted. 110

It is also desirable that the outer lifting element or elements should be held against vertical movement during the upward travel of the inner element or elements. To accomplish this and prevent the outer element 115 from being lifted, through frictional contact or otherwise, with the inner element, I have provided a detent which normally locks the outer element in its lowermost position and is automatically released, just prior to 120 125 130

the time that the inner lifting element picks up the outer lifting element. As here shown, this device comprises a dog 22 pivotally mounted in the collar 15, at the upper end 5 of the outer lifting element, and arranged to engage a lug or shoulder 23 on the standard 1 near the top thereof. In the present construction the side wall of the standard is provided with a small housing to receive the 10 end of the dog 22, which projects below the collar, and a lug or shoulder 23 is arranged within this housing. A spring 24 acts upon the dog to cause it to automatically engage the shoulder and to hold it in engagement 15 therewith. Means are provided whereby the upward movement of the inner lifting element will move this dog out of engagement with the shoulder just prior to the beginning of the movement of the outer lifting element. In the present arrangement, the dog has connected therewith a finger 25 having a laterally extending portion which extends through a slot 26 in the outer lifting element and into the path of a projection 27 20 carried by the inner lifting element just above the lug 13 and so arranged that it will engage the pin 25 and move the dog into an inoperative position just before this lug 13 engages the corresponding lug 14 on the 25 outer lifting element, thus automatically releasing the outer lifting element and permitting it to move upward when the lugs 13 and 14 are brought into engagement.

In order that the lifting elements may be 30 lowered under load, I prefer to provide the lifting pinion 7 with a worm operating mechanism, by means of which the racks may be slowly lowered, the detent pawl 12 having been first disengaged from the 35 ratchet wheel 9, and which may also be utilized to elevate the racks if desired. This worm mechanism may take various forms but, as here shown, see Figs. 4 to 6, it comprises a worm wheel 28 mounted on the shaft 40 of the pinion 7 on that side of the standard 1 opposite the ratchet wheel 9, and meshing with a worm 29 journaled in suitable brackets 30 carried by the standard and having a handle 31 by means of which it may be rotated. It is, of course, necessary that the worm should be disconnected from the pinion while the latter is being operated by the lever, and I have, therefore, mounted the worm loosely on the end of the shaft 8, 45 which carries the pinion 7, and have provided the same with a flange having arranged internally thereof a circumferential series of ratchet teeth 32. These ratchet teeth are engaged by pawls 33 which are 50 pivotally mounted on a plate 34 arranged within the flanged worm wheel and rigidly secured to the shaft 8. Springs 35 hold the pawls normally in engagement with the ratchet teeth, and hence, when the worm 29 55 is rotated the teeth will engage the pawls and transmit rotary movement through the plate 34 to the shaft 8. And when it is desired to lower the device, the worm 29 is turned in a reverse direction and the load on the shaft 7 will cause the pawls to follow 60 the ratchet teeth as the worm wheel is rotated. The springs 35 are so connected with the pawls that when the latter are moved inwardly the springs will be carried across the axes of the respective pawls and will 65 thus serve to hold the pawls in their inner or inoperative positions, thereby disconnecting the worm wheel from the pinion 7 and permitting the latter to be operated by the lever. Suitable operating mechanism may 70 be provided for moving the pawls into and out of their operative positions and, in the present instance, I have loosely mounted a plate 36 on the end of the shaft 8 and have provided this plate or disk with inclined 75 slots 37 through which extend pins 38 carried by the pawls, these pins being preferably the same pins to which the springs 35 are connected. The disk is provided with means, such as a knob 39, for rotating the 80 same and it will be apparent that upon a partial rotation of the disk the inclined slots 37 will act upon the pins to move the pawls inwardly and out of engagement with the ratchet teeth, in which position they will 85 be held by the springs 35. I also prefer to mount within the collar 15 a roller 40 against which the lifting element 5 bears and which serves to hold the same out of contact with the fixed walls of the structure 90 and to reduce the frictional resistance to its movement.

The mechanism so far described is embodied in a lifting jack but this same mechanism may, as has been above stated, be embodied without material alteration in hoisting mechanisms of various kinds and in that form of the device shown in Figs. 7 and 8 I have embodied this same mechanism in a hoisting mechanism comprising a number of 105 lifting elements and having these lifting elements of considerable length so that the structure can be extended to a great height if desired, and I have also shown the mechanism as mounted upon a truck so that it is 110 readily portable from one place to another. The general construction and arrangement of the lifting elements is similar to that already described and the structure as a whole comprises an outer casing or standard 115 41 which is pivotally mounted upon a supporting structure. This supporting structure may be of any suitable character but, as here shown, it consists of a turntable 43 rotatably mounted upon a truck. The 120 standard or outer casing 41 has rigidly secured thereto a hollow shaft 44 which is journaled in bearing brackets 45 rigidly secured to the turntable. The shaft is arranged some distance from the end of the 125 130

standard 41 and the supporting structure or turntable is so constructed that the end of the standard can swing through the same to permit the latter to be moved into a horizontal or a vertical position. With the extensible lifting elements contracted, the structure may be laid flat upon the truck for transportation. When it is desired to use the same, it is swung upward to a vertical position or to such an inclination as may be desired. To elevate the hoisting mechanism and retain the same in its adjusted position, I have rigidly secured to the opposite sides of the standard 41 segmental toothed racks 46 which mesh with pinions 47 rigidly secured to a shaft 48, on which is mounted a worm wheel 49 meshing with a worm 50 on a shaft 51, which is provided with a crank 52 by means of which it may be rotated to raise and lower the hoisting mechanism about the shaft 44. The hoisting mechanism may consist of any suitable number of lifting elements and, in the present construction, I have shown it as comprising four, an outer element 53, intermediate elements 54 and 54^a, and an inner element 55. These several elements are provided with racks on their faces which mesh with a transverse pinion 56 in a manner similar to that above described. Rigidly secured to the pinion is a beveled gear 57 meshing with a second gear 58 on the upper end of a shaft 59 extending alongside of the standard 41 and having at its lower end a beveled pinion 60 which meshes with a similar pinion 61 on a shaft 62 which is journaled in the shaft 44, the latter being hollow to receive the same. A crank 63 rigidly secured to the shaft 62 provides means for rotating the same together with the shaft 59 and pinion 56. This construction enables the lifting pinion to be placed at the upper end of the standard 41 while the driving mechanism is placed near the lower end of the standard 45 where it is more readily accessible. Each lifting element is provided with a detent comprising a pinion 64, ratchet 65, and an automatically operable dog 66, similar to those above described, and so arranged that the several lifting elements will be automatically and successively released as each preceding element completes its downward movement. Likewise, both the outer lifting element 53 and the intermediate lifting elements 54 and 54^a are provided with detents 67 to hold the same normally in their lowermost positions, these detents being tripped, in the manner above described, as the inner lifting element 55 and the intermediate lifting elements 54 and 54^a, respectively, reach the upper limits of their movements. The automatic operation of the locking devices is of special value to a mechanism such as that now being described, as the length of 60 the lifting elements is such that these parts

are elevated above the supporting platform such a distance that they could not practically be operated by hand and the automatic operation of these locks makes possible the application of the mechanism to 70 such uses as that here described.

In order to operate the hoisting mechanism under a heavy load, I prefer to provide the same, in addition to the crank 63, with a worm gear, by means of which the lifting 75 pinion may be operated. In this manner, very great power may be applied to the mechanism, although the speed attainable is less than that which can be had with the crank 63. To this end I have mounted on 80 that end of the shaft 62 opposite the crank 63 a worm wheel 68 which meshes with a worm 69 on a shaft 70 provided with a crank 71. The construction of the worm wheel and the manner of operating the same are 85 the same as have already been described and permit the worm gearing and the crank 63 to be independently operated.

The turntable upon which the hoisting mechanism is mounted may be of any suitable kind and, as here shown, it comprises a fixed ring 72 which is rigidly secured to and forms in effect a part of the truck frame 73. This fixed ring of the turntable is provided with brackets 74 cast integral therewith and adapted to receive and to be rigidly bolted to the members of the truck frame 73, thus firmly uniting these parts into a single structure. Arranged within the fixed member or ring 72 of the turntable is a movable 90 member or ring 75 which is supported by, and is rotatable upon, the fixed member. As here shown, the fixed member 72 is provided with an inwardly extending annular rib 76 which extends into a similar recess 77 95 forming the rotatable member 75. Anti-friction rollers 78 and 79 arranged in the recess 77 engage the edge and top and bottom surfaces of the rib 76 and facilitate the movement of the member 75. The movable 100 member 75 has secured thereto frame members or platforms 80 upon which are mounted the several parts of the hoisting mechanism. These platform members are spaced apart to permit the lower end of the extensible structure to move between them as the latter is moved from a horizontal to a vertical position and the turntable is provided with an opening, as shown in Figs. 8 and 9, to permit the passage of the end of 105 the extensible structure when the turntable is in its normal position. Each member of the turntable may be provided with a permanent opening, but I prefer that in the fixed member the space or opening should 110 be normally closed and I have, therefore, shown this space or opening as bridged by a section 81 of the fixed member of the turntable which is hinged at one end to the main body of said fixed member, on a horizontal 115

axis. Consequently, this section will be normally in place to receive and coöperate with the movable member of the turntable as the latter travels about the fixed member 5 but, when it is desired to lower the extensible structure into a horizontal position, this hinged section of the fixed member can be readily moved out of the way, or the end of the extensible structure may be permitted to 10 engage the same as it rises and thus automatically move it out of the way. Rotatory movement may be imparted to the movable member of the turntable in various ways, but I prefer to provide the fixed member 15 of the turntable on its outer edge with teeth 82 with which meshes a pinion 83 carried by a shaft 84 rotatably mounted on the movable member of the turntable. As here shown, this shaft is journaled in a vertical bearing 20 in the platform on the turntable and is provided at its upper end with a worm wheel 85 with which meshes a worm 86 having a crank 87 by means of which it may be rotated. The shaft of the worm may 25 be extended in any direction to locate the operating handle in the most convenient location, either at the front or the rear of the mechanism, but in the present instance I have, for the purpose of convenience, provided the worm with a short shaft so that 30 the operating crank is arranged at the rear end of the platform.

The construction and arrangement of the telescoping lifting elements may take various forms but, particularly in a mechanism such as that shown in Figs. 7 and 8, it is desirable that this should be as light and compact as possible while retaining the necessary strength. I have, therefore, as 35 shown in Fig. 11, formed the body portions of the elements of thin light material, such as sheet metal, to the forward edges of which I have attached the racks which are of heavier material, such as castings. Preferably, the several elements are so connected 40 one to the other or braced against one another as to hold them against relative lateral movement in any direction without interfering with their relative longitudinal movement. To this end the several racks or 45 castings, which are indicated as a whole by the numerals 53, 54, 54^a and 55, are provided on their opposite sides with flanged 50 projections 88, the flanges extending lengthwise of the racks and facing forwardly and rearwardly on the respective sides of each rack. The flange on one side of the outermost rack interlocks with a similar flange 55 extending inwardly from the casing 41, while the flange on the opposite side of that 60 rack interlocks with the flange on the adjacent side of the next rack, and so on. It will be noted that not only do these interlocking flanges hold the several racks against 65 forward relative movement, but they also

hold them against transverse relative movement, and this without interfering in any way with the free sliding movements of the several racks. The thin sheet metal bodies of the lifting elements are preferably arranged directly in line with the racks so that the thrust will come directly thereon without twist or strain. In order that the several elements may be braced one against the other at their rear portions without causing any large amount of frictional contact, I have provided each element at each rear corner with vertical bearing bars 89, which are preferably in the form of angle bars, arranged in the inner corner and on the outer corner of the section, the bars on the adjacent sections bearing one against the other. These bearing bars stiffen the construction of the lifting elements, hold the same in their properly spaced relation and form contact points between the several sections, thus providing a free relative movement with a minimum of frictional contact.

As has been stated, this hoisting mechanism may be used for various purposes and I have shown the mechanism illustrated in Figs. 7 and 8 equipped with apparatus to constitute the same a hose tower, by means of which nozzles attached to fire hose may be elevated to the desired height and there manipulated to direct the streams of water onto the fire. The application of this apparatus to the mechanism will require no changes in the mechanism but the mere addition thereto of certain parts. The upper end of the innermost lifting element 55 is provided at its upper end with a socket 90 adapted to receive and removably support any apparatus which it may be desired to attach thereto. In the socket there is mounted, in the present instance, a shank 91 of a yoke 92 which extends upwardly beyond the lifting element 55 and carries supporting and adjusting mechanism for several lines of fire hose 93 and their nozzles 94. Journaled in the arms of the yoke 92 is a shaft 95 to which is rigidly secured a supporting collar or sleeve 96 and on which in turn is rotatably mounted a nozzle-supporting member 97, this supporting member being rotatable about an axis intersecting the axis of the shaft 95 at right angles. Rigidly secured to the supporting member 97 and arranged in the same plane therewith is a segmental rack 98 which meshes with a beveled gear 99 which is carried by a sleeve 100 journaled on the shaft 95 near one end thereof. When the sleeve 100 is rotated the nozzle-supporting member 97 will be moved about its axis and the nozzles will be swung to the right or to the left, according to the direction of the movement of the sleeve. The rotation of the shaft 95 will serve to raise or lower the ends of the nozzles. In order that these movements may be imparted to the 130

nozzles from the platform 80, I have mounted on the shaft 95 and the sleeve 100 drums 101 and 102, respectively. Cables 103 and 104 are wound about these drums and have both ends carried downward. The ends of the cable 103 are wound about drums 105 and 106, mounted on one end of a shaft 107, which is journaled in suitable brackets 108 carried by the standard 41 of the extensible structure, while the ends of the cable 104 are wound about drums 109 and 110 which are rigidly secured to a sleeve 111 mounted upon the opposite end of the shaft 107. The construction of the two pairs of drums is identical, with the exception that one pair is mounted upon the shaft and the other pair is mounted upon the sleeve and, consequently, the description of the construction and operation of one pair of drums will apply to both. It may be noted here that the sleeve 111 has rigidly secured thereto a handle or operating wheel 112 by means of which it may be rotated, while a similar handle or wheel 113 is secured to the shaft 107. Referring to the drums 109 and 110, as shown in Fig. 12, it will be noted that the drum 110 is rigidly secured to the sleeve 111, while the drum 109 is loosely mounted thereon. The two drums are spaced a short distance apart and a ratchet wheel 114 is arranged between them and rigidly secured to the drum 110, while a pawl 115 is pivotally mounted on the adjacent side of the drum 109 and is arranged to engage the ratchet wheel 114. When the extensible structure is being extended the pawl 115 is disengaged from the ratchet wheel 114 so that both drums are free to rotate to permit the cable to be unwound therefrom. When the structure has been extended to the desired height, the drums are rotated by hand to tighten the cables and the pawl is moved into engagement with the ratchet wheel. The arrangement of the ratchet wheel with relation to the pawl is such that when the drum 110 is rotated in a direction to wind its cable thereon, the teeth of the ratchet wheel will move past the pawl wheel, which will ride loosely over them, thus permitting the cable to be unwound from the drum 109 as it is wound onto the drum 110, and thereby imparting rotary movement to the drum 102 and turning movement to the nozzles. When the drum 110 is rotated in the opposite direction the ratchet wheel will pick up the pawl 115, thus causing the drum 109 to rotate with the drum 110, thereby winding the cable onto the drum 109 and unwinding it in like amount from the drum 110 and imparting movement to the drum 102 and nozzles in the opposite direction. Preferably, both drums are provided with springs 116 which are placed under tension as the cable is unwound by the extension of the structure, and which serve to automatically

rewind the cable as the structure is lowered.

The construction and operation of the mechanism will be readily understood from the foregoing description thereof, and it will be apparent that I have provided a hoisting mechanism of this character which has a very long lift in proportion to its collapsed length, which is of a strong durable construction, very easily operated either under a heavy load or under a light load, and in which the lifting elements are normally locked in the desired positions and are automatically released at the proper times. Further, it will be obvious that motors or other power mechanism may be utilized for actuating the various parts of the hoisting mechanism. While I have shown and described certain embodiments of the invention, I wish it to be understood that I do not desire to be limited to details thereof, as obvious modifications will occur to a person skilled in the art.

Having now fully described my invention, what I claim as new and desire to secure by Letters Patent is:

1. In a hoisting mechanism, the combination with a standard, a plurality of overlapping extensible elements carried by said standard and means to successively impart longitudinal movement to said elements relatively to said standard, of a locking device carried by a succeeding element and adapted to lock the next preceding element against return movement, means tending to move said locking device into an operative position with relation to said preceding element, and a part connected with said locking device and arranged to engage a fixed part of said mechanism when said succeeding element is in its normal position, and to hold said locking device in an inoperative position.

2. In a hoisting mechanism, the combination with a standard, a plurality of overlapping extensible elements carried by said standard and means to successively impart longitudinal movement to said elements relatively to said standard, of a toothed member carried by a succeeding element against return movement and operatively connected with the next preceding element, a detent carried by said succeeding element and cooperating with said toothed member to hold said preceding element, a spring tending to move said detent into engagement with said toothed member, and a part connected with said detent and arranged to engage a relatively fixed part of said mechanism when said succeeding member is moved to its normal position and to move said detent out of engagement with said toothed member and to retain the same out of engagement therewith.

3. In a hoisting mechanism, the combination with a standard, a plurality of overlapping

- ping extensible elements carried by said standard and provided with teeth on their adjacent faces, and lifting mechanism acting on said teeth to successively impart longitudinal movement to said elements relatively to said standard, of a pinion carried by a succeeding element and meshing with the teeth of a preceding element, a ratchet wheel connected with said pinion, a pawl carried by said succeeding member, a spring tending to move said pawl into engagement with said ratchet wheel, and a part connected with said pawl and arranged to engage a relatively fixed part of said mechanism to move said pawl out of engagement with said ratchet wheel when said succeeding member is moved to its normal position and to retain said pawl out of engagement therewith so long as said succeeding element is in its normal position.
4. In a hoisting mechanism, the combination with a standard, a plurality of overlapping extensible elements carried by said standard and means to successively impart longitudinal movement to said elements relatively to said standard, of a collar secured to the upper end of a succeeding element, locking mechanism carried by said collar and arranged to operatively engage a preceding element to hold the latter against downward movement, said locking mechanism comprising a toothed member, a detent, a spring tending to move said detent into engagement with said toothed member, and a part connected with said detent and arranged to engage a relatively fixed part of said mechanism and move said detent into an inoperative position when said succeeding element is moved to its normal position.
5. In a hoisting mechanism, the combination with a standard, a plurality of overlapping extensible elements carried by said standard and provided with teeth on their adjacent faces, and lifting mechanism acting on said teeth to successively impart longitudinal movement to said elements relatively to said standard, of a collar secured to the upper end of a succeeding element, a pinion rotatably mounted in said collar and adapted to mesh with the teeth of a preceding element, a ratchet wheel connected with said pinion, a pawl carried by said collar and adapted normally to engage said ratchet wheel to lock said preceding element against downward movement, and a part connected with said detent and arranged to engage a relatively fixed part of said mechanism to move said detent out of engagement with said ratchet wheel when said succeeding element is moved to its normal position.
6. In a hoisting mechanism, the combination with a standard, a plurality of overlapping extensible elements carried by said standard and means to successively impart longitudinal movement to said elements relatively to said standard, of a separate locking device for each succeeding element to lock the same against longitudinal movement relatively to said standard and means to automatically release each succeeding element when the next preceding element has been extended to substantially the limit of its movement relatively thereto.
7. In a hoisting mechanism, the combination with a standard, a plurality of overlapping extensible elements carried by said standard and means to successively impart longitudinal movement to said elements relatively to said standard, of means to normally lock each succeeding element against longitudinal movement relatively to said standard, and means controlled by the next preceding element to render said locking means inoperative and thus release said succeeding element for longitudinal movement.
8. In a hoisting mechanism, the combination with a standard, a plurality of overlapping extensible elements carried by said standard and means to successively impart longitudinal movement to said elements relatively to said standard, of a detent carried by a succeeding element and adapted to engage a relatively fixed part of said mechanism to lock said succeeding element against longitudinal movement and means actuated by a preceding element to move said detent into an inoperative position and thus release said succeeding element for longitudinal movement.
9. In a hoisting mechanism, the combination with a standard, a plurality of overlapping extensible elements carried by said standard and means to successively impart longitudinal movement to said elements relatively to said standard, of co-operating locking parts carried by said standard and the last element to be operated to lock said element against longitudinal movement relatively to said standard, means actuated by the element preceding said last element to release said last element from said locking parts, other locking parts carried by said last element and the element preceding the same to lock said preceding element against longitudinal movement relatively to said last element, and means actuated by an element preceding the said preceding element to release the latter from said locking parts.
10. In a hoisting mechanism, the combination with a standard, a plurality of overlapping extensible elements carried by said standard and means to successively impart longitudinal movement to said elements relatively to said standard, of a collar carried by a succeeding element, a locking member carried by said collar and co-operating with a relatively fixed part of said mechanism to lock said succeeding element against longitudinal movement relatively to

said fixed part, and means carried by a preceding element to actuate said locking member to release said succeeding element for longitudinal movement.

5 11. In a hoisting mechanism, the combination with a standard, a plurality of overlapping extensible elements carried by said standard and means to successively impart longitudinal movement to said elements relatively to said standard, of a collar secured to the upper end of a succeeding element, a locking member mounted on said collar and held normally in locking engagement with a relatively fixed part of said mechanism, a finger carried by said locking member and arranged to be engaged by a shoulder on a preceding element to move said locking member into an inoperative position and release said succeeding element.

10 12. In a hoisting mechanism, the combination with a standard, a plurality of overlapping extensible elements carried by said standard and means to successively impart longitudinal movement to said elements relatively to said standard, of a collar secured to the upper end of a succeeding element, a detent pivotally mounted on said collar and arranged to engage a shoulder on said standard, a spring tending to hold 15 said detent normally in engagement with said shoulder, a finger connected with said detent and having a part extending transversely of said succeeding element, and a shoulder carried by the preceding element to engage said part of said finger to move said detent into an inoperative position.

13. In a hoisting mechanism, the combination with a standard, a plurality of overlapping extensible elements carried by 40 said standard and means to successively impart longitudinal movement to said elements relatively to said standard, of a collar secured to the upper end of a succeeding element, locking mechanism carried by said 45 collar and arranged to act upon the next preceding element to lock the same against downward movement, said locking mechanism comprising a part adapted to engage a relatively fixed part of said mechanism to 50 render said locking mechanism inoperative when said succeeding element is moved to its normal position, a second locking device carried by said collar and coöperating with a relatively fixed part of said mechanism to 55 lock said succeeding element against longitudinal movement, and means actuated by said preceding element to render said last mentioned locking device inoperative and thus release said succeeding element for longitudinal movement.

60 14. In a hoisting mechanism, the combination with a standard, a plurality of overlapping extensible elements carried by said standard and having teeth on their adjacent faces and means to successively im-

part longitudinal movement to said element relatively to said standard, of a collar secured to the last element to be actuated and projecting laterally beyond the sides of said element, a pinion mounted in said collar 70 to engage the teeth of the element preceding said last element, a ratchet wheel connected with said pinion, a pawl arranged to normally engage said ratchet wheel to hold said pinion against rotation in one direction, a 75 part connected with said pawl and arranged to engage said standard when said last element is in its lowermost position to move the pawl into an inoperative position, a detent pivotally mounted in said collar and projecting beneath the lower edge thereof, said standard having a shoulder to be engaged by said detent, means to hold said detent normally in engagement with said shoulder, a finger connected with said detent and having a part extending transversely to said last element, and a part carried by said preceding element to engage said part of said finger to move said detent into an inoperative position.

80 15. In a hoisting mechanism, the combination with a standard, a plurality of overlapping extensible elements carried by said standard and having teeth in their adjacent faces, a pinion extending transversely 95 to said elements and meshing with the teeth of one of said elements and adapted to mesh with the teeth of another element after initial movement has been imparted to said other element, coöperating parts carried by 100 the first mentioned element and the succeeding element for imparting initial movement to said succeeding element, and means for rotating said pinion to actuate said elements, of a worm wheel, means for connecting said 105 worm wheel with and disconnecting the same from said pinion, and a worm meshing with said worm wheel.

16. In a hoisting mechanism, the combination with a standard, a plurality of overlapping extensible elements carried by said standard and having teeth in their adjacent faces, a pinion meshing with the teeth of one of said elements and adapted to mesh with the teeth of the other elements after initial 110 movement has been imparted to said other elements, a shaft connected with said pinion, and means for rotating said shaft and said pinion to impart movement to said elements, of a worm wheel loosely mounted on 115 said shaft and provided with ratchet teeth, a supporting member rigidly secured to said shaft, a pawl carried by said member and held normally in engagement with the ratchet teeth of the said worm wheel, and a 120 worm meshing with said worm wheel.

17. In a hoisting mechanism, the combination with a standard, a plurality of overlapping extensible elements carried by said standard and having teeth in their adjacent 125

- faces, a pinion meshing with the teeth of one of said elements and adapted to mesh with the teeth of the other elements after initial movement has been imparted to said other elements, a shaft connected with said pinion, means for rotating said shaft and said pinion to impart movement to said elements, of a worm wheel loosely mounted on said shaft and provided with ratchet teeth, a supporting member rigidly secured to said shaft, a pawl carried by said member and held normally in engagement with the ratchet teeth of the said worm wheel, a worm meshing with said worm wheel, and means to move said pawl out of engagement with said ratchet teeth to permit said pinion to be rotated independently of said worm and worm wheel.
18. In a hoisting mechanism, the combination with a standard, a plurality of overlapping extensible elements carried by said standard and having teeth in their adjacent faces, a pinion meshing with the teeth of one of said elements and adapted to mesh with the teeth of the other elements after initial movement has been imparted to said other elements, a shaft connected with said pinion, means for rotating said shaft and said pinion to impart movement to said elements, of a worm gear loosely mounted on said shaft and comprising a flange having an internal series of ratchet teeth, a plate rigidly secured to said shaft within said flange, a plurality of pawls mounted on said plate and held normally in engagement with said ratchet teeth, a second plate rotatably mounted on said shaft adjacent to said pawls and having inclined slots therein, and pins secured to said pawls and projecting through the respective slots whereby the rotation of said plate will move said pawls into or out of engagement with said ratchet teeth.
19. In a hoisting mechanism, a standard, a plurality of overlapping extensible elements carried by said standard and having teeth in their adjacent faces, a pinion extending transversely of said elements, meshing with the teeth of one of said elements and adapted to mesh with the teeth of the other elements after initial movement has been imparted to said other elements, co-operating parts carried by each preceding element and the next succeeding element to impart initial movement to said succeeding element, a shaft extending lengthwise of said standard, gearing connecting said shaft with said pinion, a second shaft arranged near that end of said standard opposite said pinion and gearing connecting said last mentioned shaft with the first mentioned shaft, and means for rotating said last mentioned shaft.
20. In a hoisting mechanism, a standard, a plurality of overlapping extensible elements carried by said standard and having teeth in their adjacent faces, a pinion mounted on said standard near the upper end thereof, extending transversely of said elements, meshing with the teeth on one of said elements and adapted to mesh with the teeth on the other elements after initial movement has been imparted to said other elements, co-operating parts carried by each preceding element and the next succeeding element to cause initial movement to be imparted to the latter, and means arranged near that end of said standard opposite said pinion for imparting rotatory movement to said pinion to cause said elements to be successively extended.
21. In a hoisting mechanism, a standard, a plurality of overlapping extensible elements carried by said standard and having teeth in their adjacent faces, a pinion mounted in said standard near the upper end thereof, extending transversely of said elements, meshing with the teeth on one of said elements and adapted to mesh with the teeth on the other elements after initial movement has been imparted to said other elements, co-operating parts carried by each preceding element and the next succeeding element to cause initial movement to be imparted to the latter, means arranged near that end of said standard opposite said pinion for imparting rotatory movement to said pinion to cause said elements to be successively extended, and means carried by each succeeding element to lock the next preceding element in its extended position relatively thereto when said succeeding element has been moved from its normal position and to automatically release said preceding element when said succeeding element has been returned to its normal position.
22. In a hoisting mechanism, a standard, a plurality of overlapping extensible elements carried by said standard and having teeth in their adjacent faces, a pinion mounted in said standard near the upper end thereof, extending transversely of said elements, meshing with the teeth on one of said elements and adapted to mesh with the teeth on the other elements after initial movement has been imparted to said other elements, co-operating parts carried by each preceding element and the next succeeding element to cause initial movement to be imparted to the latter, means arranged near that end of said standard opposite said pinion for imparting rotatory movement to said pinion to cause said elements to be successively extended, means to normally lock each succeeding element against longitudinal movement relatively to said standard and a part carried by each preceding element to actuate the locking device for the next suc-

ceeding element and release the latter for longitudinal movement.

23. In a hoisting mechanism, a standard, a plurality of overlapping extensible elements carried by said standard and having teeth on their adjacent faces, a pinion mounted in said standard near the upper end thereof, extending transversely of said elements, meshing with the teeth on one of said elements and adapted to mesh with the teeth on the other elements after initial movement has been imparted to said other elements, coöperating parts carried by each preceding element and the next succeeding element to cause initial movement to be imparted to the latter, means arranged near that end of said standard opposite said pinion for imparting rotatory movement to said pinion to cause said elements to be successively extended, a collar secured to the upper end of each succeeding element, a locking device mounted in said collar to act upon the next preceding element to hold the same in its extended position when said succeeding element has been moved from its normal position, and comprising means to automatically release said preceding element when the succeeding element is returned to its normal position, a second locking device carried by each of said collars to lock the respective succeeding elements against longitudinal movement relatively to said standard and comprising means actuated by each preceding element to release the respective succeeding elements.

24. In a hoisting mechanism, a supporting structure, a standard mounted on said structure, means for moving said standard into a horizontal position or an upright position, a plurality of extensible elements carried by said standard, means for successively moving said elements into their extended positions, and means for locking each preceding element in its extended position relative to the next succeeding element when said succeeding element is out of its normal position and for releasing said preceding element when said succeeding element is returned to its normal position.

25. In a hoisting mechanism, a supporting structure, a standard mounted on said supporting structure, means for moving said standard into either a horizontal position or an upright position, a plurality of extensible elements carried by said standard, means for successively moving said elements into their extended positions, a collar carried by each of said elements except the first, and a locking device carried by each of said collars and adapted to coöperate with a part carried by the next preceding element to lock said preceding element in its extended position when the element carrying the collar has been moved from its normal position and to release said preceding element when said last

mentioned element is returned to its normal position.

26. In a hoisting mechanism, a supporting structure, a standard mounted on said supporting structure, means for moving said standard into either a horizontal position or an upright position, a plurality of extensible elements carried by said standard, means for successively moving said elements into their extended positions, a collar carried by each of said elements except the first and a locking device carried by each of said collars and adapted to coöperate with a part carried by the next preceding element to lock said preceding element in its extended position when the element carrying the collar has been moved from its normal position and to release said preceding element when said last mentioned element is returned to its normal position, and a second locking device carried by each collar to lock the element carrying said collar normally against movement relatively to said standard, and means actuated by a preceding element to release the locked element when said preceding element has been moved to its extended position.

27. In a hoisting mechanism, a supporting structure comprising a turntable, a standard mounted on said turntable, means for moving said standard into either a horizontal position or an upright position, a plurality of extensible elements carried by said standard and having teeth on their adjacent faces, a pinion mounted on said standard near the upper end thereof and adapted to actuate said elements to successively move the same into their extended positions, operating mechanism mounted on said standard adjacent to said turntable and operatively connected with said pinion, and means for locking the several elements in their extended positions and for automatically releasing the same.

28. In a hoisting mechanism, a supporting structure, a standard, a hollow shaft secured to said standard near one end thereof and journaled on said supporting structure, a plurality of extensible elements carried by said standard and having teeth on their adjacent faces, a pinion mounted on said standard near that end thereof remote from said supporting structure and adapted to successively move the several elements into their extended positions, a second shaft journaled in said hollow shaft and operatively connected with said pinion, a crank for rotating said second shaft and a worm gearing connected with said second shaft.

29. In a hoisting mechanism, the combination with a standard, a plurality of overlapping extensible elements carried by said standard, and means to successively impart longitudinal movement to said elements relatively to said standard, of a collar carried

- by a succeeding element, a locking device carried by said collar to control the movement of one of said elements, and means to automatically actuate said locking device.
- 5 30. In a hoisting mechanism, the combination with a standard, a plurality of overlapping extensible elements carried by said standard, and means to successively impart longitudinal movement to said elements relatively to said standard, of a collar carried by a succeeding element, a locking device carried by said collar to control the movement of one of said elements, and means controlled by the movement of another element relatively to said succeeding element to actuate said locking device.
- 10 31. In a hoisting mechanism, a supporting structure, a standard mounted on said structure, a plurality of extensible elements carried by said standard, means for successively moving said elements into their extended positions, a collar carried by each of said elements except the first, and a locking device carried by each of said collars and adapted to coöperate with a part carried by the next preceding element to lock said preceding element in its extended position when the element carrying said collar has been moved from its normal position, and to re-
- 20
- 25

lease said preceding element when said last 30 mentioned element is returned to its normal position.

32. In a hoisting mechanism, the combination with a standard, a plurality of overlapping extensible elements carried by said 35 standard and means to successively impart longitudinal movement to said elements relatively to said standard, of a hollow collar carried by a succeeding element, a locking device mounted in said collar to control the 40 movement of one of said elements, and means to automatically actuate said locking device.

33. In a hoisting mechanism, the combination with a standard, a plurality of overlapping extensible elements carried by said 45 standard and means to successively impart longitudinal movement to said elements relatively to said standard, of a hollow collar carried by a succeeding element, a locking device mounted within said collar to control 50 the movement of one of said elements, and means controlled by the movement of another element relatively to said succeeding element to actuate said locking device.

In testimony whereof, I affix my signature 55 hereto.

JOHN DOLAN.
